UNITED STATES PATENT OFFICE

2,586,773

BLAST HOLE DRILLING APPARATUS

Charles F. Ball, Franklin, Pa., assignor to Joy
Manufacturing Company, a corporation of
Pennsylvania

Application April 4, 1947, Serial No. 739,460

4 Claims. (Cl. 255—51)

1

This invention relates to drilling apparatus and more particularly to an improved blast hole drilling apparatus having improved adjustable supporting means and associated counterbalancing means for the drilling tool whereby the latter may be easily and quickly adjusted into various drilling positions with respect to the work.

In drilling apparatus, such as in blast hole drilling apparatus for use in underground mines or tunnels, the drilling tool is usually pivotally mounted on a support located near the face of the work and is usually held in adjusted position on its pivotal support by means of a clamp or other locking device, and due to the weight of the drilling tool, it is generally an extremely laborious task to effect adjustment of the drilling tool since it is necessary manually to support the tool against pivotal movement on its pivotal mounting when the clamp or other locking device is released and sometimes to lift a considerable weight in adjusting it. The present invention contemplates an improvement over previous drilling apparatus by the provision of improved counterbalancing means associated with the adjustable supporting structure for the drilling tool and embodying a counterweight arranged in a novel manner with respect to the tool mounting whereby tool adjustment is facilitated. By the provision of the counterweight arranged in a novel manner with respect to the pivotal mounting of the drilling tool, the latter may be easily adjusted in various angularly related positions without the necessity of manual support of the drilling tool during such adjustment.

It is accordingly an object of the present invention to provide an improved drilling apparatus having improved adjustable supporting means and associated counterbalancing means for the drilling tool whereby tool adjustment is facilitated. Another object is to provide an improved universal pivotal mounting for a drilling tool. A further object is to provide an improved counterweight arranged in a novel manner with respect to the universal pivotal mounting for the tool whereby the latter may be quickly and easily adjusted through a wide range of angularly related positions with respect to the work. Yet another object is to provide an improved universal pivotal mounting for the drilling tool and embodying a ball-like member carried by the drill support and a socketed member carrying the drilling tool and receiving the ball-like member, together with improved means for clamping the socketed member to said ball-like mem-

2

ber in its different positions of adjustment. A further object is to provide a universal pivotal mounting of the ball and socket type for swivelly supporting a drilling tool and improved counterbalancing means associated with the pivotal mounting whereby the weight of the drilling tool is substantially counterbalanced in all positions of adjustment thereof. These and other objects and advantages of the invention will, however, hereinafter more fully appear.

In the accompanying drawings there is shown for purposes of illustration one form which the invention may assume in practice.

In these drawings:

Fig. 1 is a side elevational view of a drilling apparatus in which an illustrative form of the invention is embodied, different adjusted positions of the drilling tool being indicated in dotted lines.

Fig. 2 is a cross-sectional view taken on line 2—2 of Fig. 1, showing the mobile base of the drilling apparatus in front elevation and with the drill supporting boom swung into a lowered, lateral position.

Fig. 3 is an enlarged longitudinal vertical sectional view taken through the extensible boom frame.

Fig. 4 is a cross-sectional view taken on line 4—4 of Fig. 3.

Fig. 5 is an enlarged fragmentary view of the drilling tool and its associated counterbalancing means, with parts shown in vertical section to show structural details.

Fig. 6 is a cross-sectional view taken substantially on line 6—6 of Fig. 5.

Fig. 7 is a detail sectional view taken on line 7—7 of Fig. 5, showing the swivel clamp.

The invention, as illustratively disclosed herein, is shown embodied in a blast hole drilling apparatus of the type known as a mobile blast hole drill especially designed for use in underground mines or tunnels. Evidently, the invention may be incorporated in drilling apparatus of various other types and used for other purposes.

The drilling apparatus shown comprises a mobile base 1, herein a tractor base, comprising a frame 2 supported, propelled and steered by endless tractor treads 3, 3 of a conventional design. Mounted on a platform carried by the base frame, midway between the tractor treads, is a pedestal 5, herein preferably having its base bolted to the platform. This pedestal has a frame 6 swiveled thereon to turn about a vertical axis, and this frame is preferably formed with a clamp 7 operated by a lever 8 for securing the swiveled frame

in its different positions of adjustment with respect to the pedestal. Pivotedly mounted at 9 on a horizontal axis at the upper end of the swiveled frame 6 is an elongated, tubular, boom frame 10, herein extending outwardly in advance of the base. This boom frame is axially extensible and comprises a tubular rear boom frame part 11 and a tubular front boom frame part 12, the latter being telescopically arranged within the rear boom frame part, for a purpose to be later explained. The boom frame part 12, as shown in Fig. 3, is provided with a longitudinal splineway 13 engaged by a spline 14 secured, as by a screw 15, to the rear boom frame part 11 near its forward end, and this spline and splineway connection permits axial extension of the boom frame while precluding rotation of the front boom frame part 12 with respect to the rear boom frame part 11. Carried near the outer end of the rear boom frame part 11 are transverse clamping bolts 16, 16 each engaging a pair of cooperating clamp elements 17, 17 guided in transverse bores in the frame part 11 and movable into frictional engagement with the exterior periphery of the front boom frame part 12. Each bolt 16 passes through a bore in one clamp element and is threadedly connected to the other clamp element in the manner shown in Fig. 4, and both the clamp elements are held against rotation in their bores by means of conventional pin and slot connections 18 but are free to slide. The clamp elements of each pair are constantly urged apart, toward their outer released position, by means of a coil spring 19 arranged therebetween and surrounding the bolt, as shown. The bolts are formed with outer polygonal head portions 20 engaging the adjacent clamp elements and shaped for engagement by a suitable turning instrument whereby the bolts may be tightened to move the clamping elements 17 toward one another. When the bolts are tightened, the clamp elements are moved into frictional engagement with the front boom part 12, firmly to clamp the latter in axially adjusted position with respect to the rear boom part 11. For swinging the boom frame 10 in a vertical direction about its pivot 9 with respect to the swiveled frame 6, a hydraulic piston and cylinder type jack 21 has its cylinder pivotally connected at 22 at its rear end to the lower portion of the swiveled frame 6 and its piston rod 23 pivotally connected at its upper end at 24 to the underside of the rear boom part 11, as clearly shown in Fig. 2. When fluid under pressure is supplied to this jack, the boom frame 10 may be swung in a vertical direction about its pivot, and when fluid is released from the jack, the boom frame may be rapidly lowered, in an obvious manner. By trapping fluid in the jack at the opposite sides of the jack piston, the boom frame 10 may be firmly locked in adjusted position. Universally pivotally supported, in a novel manner, at 25 at the outer extremity of the boom frame 10 is a conventional drilling tool generally designated 26. This drilling tool may assume various forms but is herein preferably of the electric type having a drilling instrument 27 driven by an electric motor 28. The drilling instrument is herein in the form of a conventional auger drill steel carrying a drill bit 29, and having its shank received in a drill chuck 30. Projecting rearwardly from the drill motor within a tubular housing 31 is a conventional drill feeding means for feeding the drill steel toward the work as it is rapidly rotated in a well known manner.

The improved universal pivotal mounting 25 for the drilling tool is herein preferably of the ball and socket type and has associated therewith, in a novel manner, counterbalancing means, generally designated 32, whereby the drilling tool 26 may be easily and quickly adjusted, without great manual labor, through a wide range of angularly disposed drilling positions with respect to the boom frame. In this improved construction, 5 suitably fixed to the outer extremity of the front boom frame portion 12 is an axially disposed, outwardly projecting, tapered shaft 33, and the ball member 34 of the ball and socket pivotal mounting has a tapered socket 35 for receiving the tapered shaft and is rigidly held on the shaft by a tightening nut 36 threaded at 37 on the outer end of the shaft. The ball member 34 is keyed at 38 to the shaft 33 to fix the ball member 34 against rotation with respect to the shaft. Receiving the ball member and engaging the smooth exterior spherical surface thereof are the walls of a hemispherical socket 39 formed in a drill support 40, and the drilling tool 26 has a projection 41 suitably rigidly attached to a similar projection 42 on the drill support 40. The drill support 40 may be held in position on the ball member 34 by means of a clamping ring 43 secured by bolts 44 to the drill support; and a pair of screws at one side of the ring have adjusting nuts 45, threaded 10 thereon as shown in Fig. 7 and each provided with a turning lever 46. When the nuts 45 are tightened, the clamping ring 43 is drawn toward the drill support, thereby firmly to clamp the parts against movement with respect to the ball member 34. Arranged on the drill support substantially diametrically opposite from the projection 42 is an elongated projection 48 which carries a counterweight 49.

Assuming the parts to be disposed with the drill axis parallel to and in the same horizontal plane with the boom axis when the latter is horizontal, the counterbalancing will be so effected, by properly locating the centers of mass of the drilling tool and of the counterweight and determining the mass of the counterweight, that there will be no material rotative tendency about an axis in the same straight line with the axis of the boom or about a horizontal axis passing through the center of the ball and at right angles to the boom axis. The weight distribution will 15 also be such that when the tool axis is in the same vertical plane with and parallel to the boom axis there will be no material rotative tendency about a horizontal axis perpendicular to the line of the boom axis at the center of the ball. In effect, the counterbalancing is effected by so determining and locating the drilling tool and the counterweight relative to the center point of the ball that the centers of mass of the drill and counterweight are each in a common straight line passing through the center point of the ball and that the product of the mass of the drilling tool and its moment arm (distance of its center of mass from the center of the ball) is equal to the product of the mass of the counterweight 20 multiplied by its moment arm (distance of its center of mass from the center of the ball), both distances measured along the common straight line in which the centers of mass and the center of the ball lie.

The mode of use of the improved drilling apparatus is as follows: The apparatus may be propelled about the mine by the endless tractor treads 3, 3, and steering of the apparatus may be effected, in a well known manner, by varying the 25

relative speeds of the tractor treads. When the working place is reached, the boom frame may be axially extended as desired and may be swung laterally to the desired position and the jack 21 may be operated to vary the inclination of the boom frame. The boom frame may be extended or retracted, as desired, simply by loosening the clamp elements 17 upon adjustment of the clamping bolts 16 and sliding the front boom frame part 12 axially with respect to the rear boom frame part 11 and, upon suitable adjustment, the clamp elements may again be tightened. The swiveled drill frame 6 may be locked in position simply by swinging the lever 8 to tighten the clamp 7. The drilling tool 26 may be swiveled into the desired angular position with respect to the boom frame on its universal pivotal mounting 25 simply by loosening the clamp nuts 45 and swinging the drilling tool on its pivotal mounting, and thereafter the clamping bolts may be tightened firmly to hold the tool in its position of adjustment. During this latter adjustment, the counterweight 49 serves substantially to counterbalance the weight of the drilling tool thereby to make adjustment thereof comparatively easy. The counterweight is so arranged with respect to the pivotal mounting and the drilling tool that the tool support may be swung into various angular positions wherein the longitudinal axis of the tool extends along lines perpendicular to lines intersecting the center of the ball member of the ball and socket mounting. Thus the tool may be swung arcuately through a series of positions parallel with the longitudinal axis of the boom frame, about a transverse axis in planes in which the tool lies, or about an axis at right angles to both of said axes. The counterbalance weight serves substantially to counterbalance the weight of the drilling tool regardless of whether the drill is in horizontal drilling position, in vertical drilling position, or in any intermediate drilling position between the horizontal and the vertical.

As a result of this invention, an improved blast hole drilling apparatus is provided having improved adjustable supporting means together with associated counterbalancing means whereby adjustment of the drilling tool may be effected easily and rapidly. By the provision of the improved supporting structure including the extensible boom frame and the universal pivotal mounting for the drilling tool, a wide range of tool adjustment is possible. The particular arrangement of the counterweight with respect to the pivotal mounting and the drilling tool enables adjustment of the drilling tool through a wide range of angularly related positions with comparatively little effort on the part of the operator. The structure is relatively simple and rugged in design, well adapted to meet the demands of service in underground mines. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

- 5 1. In a drilling apparatus, the combination comprising a support, a drilling tool, a universal ball and socket pivotal means for mounting said tool on said support whereby said tool may be pivoted about said support relative to three axes which intersect at the center point of said ball and socket pivot, a counterbalancing weight for said tool for counterbalancing the latter in all of its positions of movement about said axes, one member of said ball and socket pivotal means having oppositely projecting extensions to which said tool and said counterweight are respectively 10 rigidly secured, whereby said tool and said counterweight always move in unison, the centers of mass of said tool and said weight disposed in a common straight line passing through said center 15 point and so spaced from said center point that the products of the mass of each of said tool and said weight by the length of its moment arm from said point are equal.
- 10 2. A drilling apparatus as set forth in claim 1, 25 wherein a clamping device cooperates with the socketed member of said ball and socket pivotal means and includes a clamping ring engaging the ball member at the opposite side thereof from said socketed member, and bolts are provided 30 for tightening said ring thereby to secure the drilling tool in its different positions of adjustment with respect to said support.
3. A drilling apparatus as set forth in claim 1, 35 wherein the centers of mass of said counterweight and said drilling tool when the latter is perpendicular to the working face are disposed at opposite sides of a transverse plane passing through said center point of said pivotal mounting means and cutting through both said counterweight and said tool.
4. A drilling apparatus as set forth in claim 1, 40 wherein said counterweight and said drilling tool are disposed diagonally opposite each other and at opposite sides of said center point, with the center of mass of said counterweight spaced forwardly of said pivotal mounting means with respect to the center of mass of said drilling tool, when the center of mass of said tool is disposed rearwardly with respect to said center point of said ball and socket pivotal means.
